(21) Appl. No.: **29/105,411**

Primary Examiner—M. H. Tung

(22) Filed: **May 24, 1999**

CLAIM

(51) LOC (7) Cl. **14-02**

The ornamental design for a face plate for a data storage enclosure, as shown.

(52) U.S. Cl. **D14/114**

DESCRIPTION

(58) Field of Search D14/114, 100,
D14/105, 107, 109; D13/184, 162, 199;
361/680-5, 728-36; 360/99.01-99.12; 312/208.1

FIG. 1 is a front perspective view of the face plate;

FIG. 2 is a back view thereof;

FIG. 3 is a top view thereof;

FIG. 4 is a bottom view thereof;

FIG. 5 is left side view thereof; and,

FIG. 6 is a right side view thereof.
